(57) **CLAIM**

The design for a dispenser for cosmetics, as shown and described.

DESCRIPTION

FIG. 1 is a top, front, left perspective view of the dispenser for cosmetics showing my new design in its assembled state; FIG. 2 is a front elevational view thereof; FIG. 3 is a left side elevational view thereof; FIG. 4 is a rear elevational view thereof; FIG. 5 is a right side elevational view thereof; FIG. 6 is a top plan view thereof; and FIG. 7 is a bottom view thereof; FIG. 8 is a top, front, left perspective view of the container portion of the design, shown separated from the wall holder for a clear and complete disclosure thereof; FIG. 9 is a front elevational view thereof; FIG. 10 is a left side elevational view thereof; FIG. 11 is a rear elevational view thereof; FIG. 12 is a right side elevational view thereof; FIG. 13 is a top plan view thereof; and FIG. 14 is a bottom view thereof; FIG. 15 is a top, front, left perspective view of the wall holder portion of the design, shown separated from the container for a clear and complete disclosure thereof; FIG. 16 is a front elevational view thereof; FIG. 17 is a left side elevational view thereof; FIG. 18 is a rear elevational view thereof; FIG. 19 is a right side elevational view thereof; FIG. 20 is a top plan view thereof; and, FIG. 21 is a bottom view thereof.

The broken lines are included for the purpose of illustrating the portions of the dispensing container that form no part of the claimed design.

1 Claim, 18 Drawing Sheets
